Howard A. Hill

UNITED STATES PATENT OFFICE

IRVING SCHMIDT, OF BROOKLYN, NEW YORK

HAND-BAG CLASP

Application filed July 19, 1928. Serial No. 293,846.

My invention relates to improvements in handbags and more particularly has reference to and is illustrated in the accompanying drawings, in its application to a lady's handbag such as is usually used for carrying the purse and other small articles of requirement. One of the principal objects of the invention is to provide a convenient, durable and secure locking and fastening means in combination with the frame of the bag, which is preferably made of celluloid or other suitable material.

Fig. 1 illustrates in perspective a suitable handbag frame in closed position embodying an application of my invention. Fig. 2 is a similar view showing the frame in opened position. Fig. 3 is a closed section on the line 3—3 of Fig. 1, looking from right to left therewith, and Fig. 4 is a closed section of the lock or fastening mechanism illustrating a modification.

5 indicates one of the jaws of the frame, and 6 the other jaw preferably connected thereto as indicated at 7, the jaw 5 preferably 25 providing an inset portion 8, in which the jaw 6 is seated so that when closed, the said jaws are flush, as shown in Fig. 1. As a preferable means of providing for this, the jaw 5 has suitably cemented or otherwise secured thereto, or formed therewith, a part 9, cut away to receive the jaw 6, and of the same thickness of the jaw 6.

Bearings 10 are preferably formed upon the upper part of the jaw 5, and are penetrated by a pin 11, upon which the fastening flap 12 turns, preferably with some friction, said flap having a pin 13 and beveled out portion 14, so that when in closed position as shown in Fig. 1, the pin 13, secured in the flap 12, may be withdrawn from the hole 15, in the jaw 6, by inserting the end or finger beneath the beveled cut away portion 14, of the flap 13, throwing said flap forwardly as shown in Fig. 2 and thereby releasing the jaw 6, allowing the bag to be opened.

When closing the bag, the pin 13 upon entering the hole 15, exerts a slightly forward pull upon the same, thus securely retaining the bag in closed position until released as aforesaid. 16, 17, indicate lugs also from the

jaw 5, for a chain, strap, or other suitable means for carrying the same.

In the modification shown in Fig. 4, it will be observed that the top of the jaw 6 is preferably slightly tapered so that the inside of the same indicated at 18 is slightly higher than the outside indicated at 19, and a reversed taper or bevel may be provided upon the front portion 9 of the jaw 5 so as to allow the jaws to clear when closing but, when the pin or button 13 is pressed into the hole 15, the jaw 6 is thereby lifted from the position shown in dotted line at 18 to the position shown in full line at 19, Fig. 4 thereby securely holding the upper edge of the jaw 6, 60 behind the lower edge of the portion 9 of the jaw 5.

Of course it will be understood that various modifications may be made in the construction and arrangement of parts without departing from the spirit of the invention as claimed.

I claim:—

In a bag of the class described, an opening therefor, comprising a pair of pivoted jaws, 75 one of the said jaws inset in one side of the other of the said jaws, a flap pivotally mounted upon said other jaw and engaging means for securing said flap to said inset jaw when in closed position, said jaws beveled from 80 the outside inwardly and upwardly.

In testimony whereof I hereunto affix my signature.

IRVING SCHMIDT.
